PANIC-RELEASE DOORLOCK

Gottlieb Radke and Samuel Schlaub, New York,
N. Y., assignors to Safe-T-Lock Co., New York,
N. Y.

Application December 15, 1931
Serial No. 581,096

1 Claim. (Cl. 292—37)

This invention relates to panic bolt mechanisms such as are employed for the exit doors of theaters, schools, and other places of public assembly.

5 One of the objects of the invention is to provide a panic release door lock, including a plurality of locking bolts and a pivotally mounted release bar for manual operation, which shall have the advantages of simple and inexpensive 10 construction and reliable operation and which at the same time may be positively released on swinging of said release bar in either direction.

Another object is to provide a panic release door lock as just stated, wherein, although swinging 15 of the release bar retracts all bolts simultaneously, a forcing of one bolt to retracted position, as by the use of a jimmy or the like in the hands of a person seeking surreptitiously to enter the premises, will not retract the plurality of bolts.

20 The invention will be more clearly understood and the foregoing and other objects and advantages thereof fully appreciated from the following description of an embodiment of the invention as now preferred and as illustrated and 25 shown in the accompanying drawing, in which:

Fig. 1 is a view showing said embodiment in side elevation and showing the carrying door in edge elevation;

Fig. 2 is a vertical section taken substantially on 30 the line 2—2 of Fig. 3;

Fig. 3 is a vertical section taken substantially on the line 3—3 of Fig. 2;

Fig. 4 is a horizontal section taken substantially on the line 4—4 of Fig. 3, with certain of 35 the parts shown in top plan;

Fig. 5 is an enlarged detail view showing certain parts of Fig. 2 rearranged to retract both bolts; and

Fig. 6 shows in perspective on a somewhat reduced scale one of the parts of Fig. 5.

Similar reference characters refer to similar parts throughout the several views.

Referring to the drawing more in detail, the lock shown includes a plurality of oppositely extending bolts 10, these running up and down a swing door 12. Said bolts are guided near their outer ends by brackets 14 carrying collars 14a, and near their inner ends by sleeved extensions 15' of a casing 15.

50 When the door is closed, as shown in Fig. 1, the outer ends of the bolts enter suitable keepers 16 in the top and bottom sills of the door framing.

Each bolt is shown in the present case as including a long tube 10a and a portion of a device

forming part of the mechanism for simultaneously retracting both bolts for emergency door release as hereinafter described. Said portion of said device includes a rod 18 extended into its tube 10a to the extent permitted by a collar 18' on the 60 rod; the rod then being riveted to its tube as indicated at 19. Beyond their collars 18', the rods 18 extend toward each other and into the interior of casing 15 through circular openings in the top and bottom walls of said casing concentric with the bores of the sleeve extensions 15' of the casing. Between the annular inner ends of said sleeve extensions and said collars are expansile coil springs 20 tending always to project the bolts 65 to maximum extension as shown in Fig. 1.

The portions of the rods 18 which are disposed in casing 15 are extended to overlap each other thereby to provide on each bolt intermediate the ends of the other bolts a crosspiece 18a or 18A. Thus the crosspiece 18a, carried by the upper 70 bolt, is always lowermost; and the crosspiece 18A, carried by the lower bolt, is always uppermost. These crosspieces, however, are connected with their bolts in such manner as always to provide room for a rocker bar or cam 21 either to lie flat- 75 wise between them as shown in Figs. 2 and 3; or to be rotated between them through a full 90° angle, as illustrated in Figs. 5 and 6, in either direction.

For ruggedness, yet light weight, the crosspieces are connected to their bolts by being 80 formed as parts of stirrup shaped yokes as will be seen best from Fig. 5. For compactness, these yokes are oppositely stepped so as to lie in parallel planes on opposite sides of the center line of a bolt, as shown in Figs. 3 and 4. For convenience in assembling, the casing 15 is made in two halves from the top of the casing at the upper 85 end of the upper sleeve extension 15' to the bottom of the casing at the lower end of the lower sleeve extension 15'. The line of split of the casing, in substantially the same plane as the plane of separation between the two yokes, is seen best in Fig. 4; the two casing halves being secured together in any suitable way, as by screws sent through the casing half to the right in Fig. 3 into 90 the tapped holes 15b (Fig. 2) in the other casing half.

When the casing is thus closed following assembly of the parts therein as above described, the cam 21 is loosely restrained between the two 105 side walls of the casing but nevertheless extends through both yokes.

Said cam 21 is carried by a short shaft 21', journaled in an annular boss 15" formed exteriorly of the casing half to the right in Fig. 3; 110

this shaft having a squared end beyond said boss. The casing 15 is secured to the door 12 in any suitable way, as by screws or the like. In the present case, such screws are shown as sent through baseplates 15a, each formed as a unitary side wing on a casing half.

Extending across the entire width of the door is a release or swing bar 22 having short parallel offset terminal portions 22a and 22b the former of which has a square hole at its door adjacent end for taking the squared end of cam shaft 21' and the latter of which is flattened to a disc to fit within a bifurcation 23' standing out from a bracket 23 screwed or otherwise suitably secured to the door. A rivet 24 pivotally mounts said disc in said bifurcation on an axis of rotation aligned with that of cam shaft 21'. The portion 22a of the swing bar is here shown as additionally secured to said cam shaft by a washer 25 held in place by a screw 26.

Operation

Normally the parts are arranged as shown in Figs. 1 to 4.

25 The cam 21 is horizontally held in that position impositively by the action of the springs 20 which act to draw the crosspieces 18a and 18A as closely together as possible. The crosspieces are now flat against the opposite flat sides of the horizontally extended cam; and both bolts are extended to locking position.

On closing the door, both bolts latch individually into their keepers 16, either simultaneously or one after the other, depending on the locations 35 of the keepers relative to their bolts; it being noted that retraction of either bolt against its spring is independent of a similar movement of the other bolt and is also independent of any movement of the cam.

40 With the door closed and locked by both bolts, it may be instantly opened by a movement of the swing bar 22 in either direction to an extent sufficient to remove the outer ends of the bolts from their keepers. As the parts are designed, the extent of movement required by the swing bar is comparatively slight. The door is unlocked on a movement of the swing bar in either direction because a rotation of the cam in either direction out of the horizontal will move both 45 crosspiece 18a and crosspiece 18A to spread the crosspieces apart; that is, the upper crosspiece 18A will be moved upward against the spring 20 therebelow to free the lower bolt, and the lower crosspiece 18a will be moved downward against the spring 20 thereabove to free the upper bolt.

50 The swing bar 22 is shown, for convenience of illustration, as extending horizontally when in normal position, that is, with the cam 21 allowing the springs 20 to extend both bolts to locking position. Preferably, however, such swing bar

normally is inclined somewhat from the horizontal. Tests have shown that about a 30° droop of the portions 22a and 22b is ideal. Then, body pressure against the swing bar, as from a mass of people crowding against the inside of the door, will in and of itself force the swing bar to a greater downward inclination toward the door sufficient to release both bolts. Also, the public has become somewhat educated to a swing bar forming part of an emergency door release which normally has somewhat of a droop, and the tendency in most cases will be to bear down on the swing bar. As already pointed out, a movement of the swing bar in either direction releases both bolts; and this is true whatever be the normal disposition of the swing bar. Should a person at the door seeking emergency exit so lose his head as not to notice the normal downward droop of the swing bar and attempt to pull up on the latter, the bar will, of course, move upward in response to that pull, and, as aforesaid, retract both bolts and release the door.

55 Yet the door can only be opened by an operation of the swing bar 22 from the inside. This is so because it is impossible to release both bolts merely by prying one out of its keeper. Only that bolt which is thus jimmied or otherwise illicitly released, as by a small boy attempting to enter a cinema theater without paying for his admittance, is moved relative to its keeper. Such a movement of either bolt is not transmitted to the other bolt; the moved bolt merely causing its crosspiece 18a or 18A to separate somewhat from the cam 21.

60 There has herein been described one specific embodiment of the invention, but it will be understood that the same is susceptible of various modifications within the spirit of the invention and the scope of the appended claim, which claim is to be interpreted as broadly as is consistent with the prior art.

65 What is claimed is:

In a mechanism of the class described, a casing, sleeve extensions projecting from said casing, tubular locking bolts slidably mounted in said sleeve extensions, operating means mounted in said casing and including relatively short rods extending into the sleeve extensions and into the end of their respective locking bolt, a collar on each of said rods for engagement with the 125 respective end of its locking bolt, and a coil spring surrounding each of said locking bolts, one end of each of said coil springs engaging the bottom of the sleeve extension in which it is mounted, with the other end of the coil spring 130 engaging the collar of the bolt which the coil spring surrounds.
